AUTOMATIC BOILER WATER CONDITIONER
AND BLOW-OFF SYSTEM

Lewis O. Gunderson and Oland W. Carrick, Chicago, Ill., assignors to Electro-Chemical Engineering Corporation, Chicago, Ill., a corporation of Delaware

Application October 9, 1936, Serial No. 104,760

23 Claims. (Cl. 122—381)

This invention relates to the collecting and discharging of collapsed foam from the upper portion of a steam boiler to remove foam forming and foam stabilizing ingredients that have been adsorbed and accumulated in the water surface and foam bubble films. More specifically, this invention relates to apparatus for discharging the water from collected collapsed foam in a boiler without waste of steam from the boiler while simultaneously actuating a blow-off valve for intermittently removing sludge and sediment from the boiler.

In the Carrick and Seniff U. S. Patent No. 2,038,414 dated April 21, 1936, there is described and claimed a foam indicating and control apparatus for steam boilers wherein the moisture entrainment in the steam above the boiler water is accurately indicated while the steam is still in the boiler by means of a collecting tube disposed in the steam space of the boiler for sampling the moisture in the steam. The collected moisture is drained through an indicating means and can actuate a blow-off mechanism for blowing down the boiler. However in this patent the boiler is blown off in the usual manner from the lower portions thereof.

We have found that the foam forming ingredients and foam stabilizing ingredients in boiler water accumulate or are positively adsorbed in the steam bubble interfaces or in the foam films. As these substances are released at the water surface upon breaking of the steam bubbles it is apparent that they are free to recirculate in the boiler water, repeating their function of bringing about foam formation and stabilization by becoming adsorbed in the surfaces of new steam bubbles formed in the evaporation zone in the boiler. These substances therefore perpetuate foam formation in the boiler unless they are removed or unless their foam forming and stabilizing ability is destroyed.

According to this invention the "light water" or the water contained in the foam films having a high concentration of foam forming and foam stabilizing ingredients is collected at the top level of the boiler water and discharged from the boiler. The apparatus of this invention provides for the removal of the concentrated boiler water containing the foam producing and foam stabilizing substances without discharging substantial amounts of steam from the boiler and therefore differs widely from previously used skimmers which consisted of perforated pipes located at the surface of the boiler water to skim off foam therefrom. These skimmers, however, permitted the

discharge of large amounts of steam and were very inefficient for blowing down the boiler to remove foam producing substances.

It is then an object of this invention to provide apparatus for removing foam producing and foam stabilizing ingredients from steam boilers in operation.

A further object of this invention is to provide apparatus for collecting collapsed foam or "light water" at the boiler water surface in an operating steam boiler and discharge this material without discharge of substantial amounts of steam from the boiler.

A further object of this invention is to provide an automatic blow-off apparatus for steam boilers actuated by water containing large amounts of foam forming and foam stabilizing ingredients that have been collected from the boiler water.

A further object of this invention is to discharge from an operating steam boiler, the water from collapsed foam collected near the upper portion of the boiler together with sludge and sediment from the lower portion of the boiler.

Other and further objects of this invention will become apparent to those skilled in the art from the following detailed description of the annexed sheets of drawings which disclose preferred embodiments of the invention.

On the drawings:

Figure 1 is a fragmentary diagrammatic side elevational view, with a part broken away and shown in cross section, of a locomotive boiler showing our invention applied thereto.

Figure 2 is a diagrammatic vertical cross-sectional view taken substantially along the line II—II of Figure 1.

Figure 3 is an enlarged elevational view of the blow-off valve illustrated in the lower right-hand corner of Figure 1.

Figure 4 is a fragmentary diagrammatic view with a part broken away and shown in cross section, of a locomotive boiler showing a modified form of our invention applied thereto.

Figure 5 is an enlarged fragmentary vertical cross-sectional view taken substantially along the line V—V of Figure 4.

Figure 6 is an elevational view of an alternative form of pipe line system for the apparatus shown in Figure 4.

Figure 7 is an enlarged vertical cross-sectional view of the blow-off valve illustrated in the lower right-hand corner of Figure 4.

As shown on the drawings:

The invention is shown as applied to a locomotive boiler but it should be understood that the

invention may be applied, as well, to other types of boilers. The locomotive boiler 10 shown in Figures 1 and 2 comprises the usual boiler shell 11 and a fire box 12 defined by the sheet 13. Boiler tubes 14 extend in communication with the fire box forwardly through the sheet 13.

Under usual operating conditions water 15 surrounds the tubes 14 and the fire box 12 and extends upwardly to the normal water line 16 which 10 is a slight distance above the crown sheet 17 for the fire box.

The space 19 between the water level 16 and the top of the boiler is the steam space of the boiler from which steam is supplied to the steam 15 dome 20 for feeding the operating cylinders (not shown) of the locomotive.

According to this invention a collecting basin 21 is located approximately at the normal water level 16 in the boiler and the bottom of the basin 20 may be slightly below or slightly elevated from that level as long as the top edges of the basin are above the normal water level. The basin 21 is suspended from the boiler shell 11 by means of straps 22 and 23 and is thus held rigidly in the 25 boiler and extends transversely thereacross without interfering with the flow of steam to the steam dome 20. The basin 21 is preferably located, as shown in Figure 1, between the steam dome 20 and the primary evaporation zone of 30 the boiler so that it will intercept any excessive foam development in the boiler that might otherwise continue toward the steam outlet in the steam dome and be entrained with the steam. When the boiler is in operation the buoyancy of 35 the steam bubbles increases the volume of the boiler water such that the top edge of the basin will be below the water level. A pipe 24 communicates with the bottom of the basin 21 and with the inlet 25 of a blow-off valve 26, which 40 may be of any usual construction. The blow-off valve when opened will cause the water in the basin 21 to be drained from the basin and discharged from boiler through a discharge line 27 communicating with the valve 26 and with a 45 steam separator 28 mounted on top of the boiler shell 11. Steam and water are separated from each other in the separator 28 and the steam discharged upwardly at 29 from the separator 28. The water is discharged through a downwardly 50 extending pipe 30 to the road bed below the boiler as at 31.

If desired the blow-off valve 26 can also discharge water from the mud ring in the boiler. For this purpose, the blow-off valve 26 is secured 55 to a flange 32 of a pipe 33 extending through the boiler shell 11 as indicated in Figure 3. The pipe 33 communicates with the mud ring of the boiler and when the valve 26 is opened, sludge and sediment will be discharged through the pipe 60 33 into the blow-off valve 26 and through the discharge pipe 27 into the steam separator 28 where the steam is separated therefrom and the sludge water is discharged to the road bed.

The blow-off valve 26 can be opened by steam 65 pressure from the locomotive boiler supplied through a pipe line 34. Admission of steam through the pipe line 34 is controlled by an operating valve 35 mounted in the cab 36 of the locomotive. When the valve 35 is opened the 70 steam pressure of the boiler is exerted in the pipe line 34 and this pressure causes the blow-off valve to open thereby discharging water from the basin 21 and sludge and sediment from the mud ring of the boiler.

75 The amount of discharge through the blow-off

valve 26 from the basin 21 or from the mud ring may be controlled by the size of the pipes 24 and 33 or by placing regulating valves such as 24a in either or both of these pipes. A shut-off valve 37 may be provided in the blow-off valve 26 to 5 permit disassembly of the blow-off valve for repair purposes without removing pressure from the boiler.

It should be understood that any type of blow-off valve can be used. 10

From the above description of Figures 1 to 3, it should be understood that the foam stabilizing and foam producing substances are concentrated at the top water level in the boiler in what is known as concentrated water or light water. 15 This light water is collected in the basin 21 and is discharged from the boiler thereby removing the foam producing and foam stabilizing materials. Since the collecting basin is drained from the bottom thereof, there is no material loss 20 of steam when the boiler is blown down.

In accordance with this invention sludge and sediment can also be blown from the boiler simultaneously with the removal of concentrated 25 boiler water.

Steam is separated from the discharged concentrated boiler water and the discharged sludge water and released to the atmosphere above the boiler. The sludge water and the concentrated water are discharged with harmless force to the 30 road bed below the locomotive.

In Figures 4 and 5 parts identical with parts described in Figures 1 and 2 have been designated by the same reference numerals.

In Figures 4 and 5, the reference numerals 40 35 and 41 designate separate buckets or basins having open tops and closed bottoms mounted in the steam space 19 of the boiler with their bottoms extending into the boiler water 15 below the normal level 16 thereof. The bucket 41 is taller than 40 the bucket 40 and extends thereabove as shown. Brackets 42 and 43 support the buckets 40 and 41 from the boiler shell 11. The position of the buckets with respect to the boiler water 15 can be adjusted such as, for example, by providing 45 slots in the straps or brackets 42 and 43.

Pipes 44 and 45 enter through the boiler shell 11 as best shown in Figure 5 and extend horizontally through the steam space 19 of the boiler into the buckets 40 and 41 respectively. The pipes 44 50 and 45 are bent downwardly in the centers of the buckets to form siphon legs 44a and 45a respectively. The siphon legs 44a and 45a terminate near the bottoms of the buckets or basins 40 and 41. By arranging the tops of the buckets at two 55 different levels in the boiler, the lower bucket 40 will collect collapsed foam before the foam level in the boiler reaches the level of the top of bucket 41. The matter collected in bucket 40 is discharged from below its surface by the siphon leg 44a into 60 the pipe 44 whenever its level in the bucket is above the siphon neck. If the foam level in the boiler continues to rise in spite of the discharge from bucket 40 collapsed foam will be collected in the bucket 41 as soon as the foam level reaches the 65 top of this bucket. Matter collected in bucket 41 is discharged therefrom from below its surface into the pipe 45 by the siphon leg 45a.

The pipe 45, outside of the boiler shell 11, feeds into a valve 46 of the steam trap type mounted on 70 the boiler near the bottom thereof as best shown in Figure 4. The valve 46 discharges into a horizontal pipe 47 extending toward the rear of the boiler.

The pipe 44, outside of the boiler shell 11, 75

terminates in a valve 48 of the steam trap type mounted on the boiler 11 near the bottom thereof. The valves 46 and 48 are adapted to be opened by water collected therein but are not 5 opened by steam. The valve 48 discharges through a pipe 49 into the pipe 47.

The siphon legs 44a and 45a prevent spasmodic operation of the steam traps 46 and 48 whenever a little water is splashed into the buckets 44 and 10 45 since water will not enter the traps until either bucket is filled above the siphon neck of the siphon legs. The traps will then operate continuously until the buckets are emptied into the lower terminus of the siphon legs.

15 Vent holes 44b and 45b (Figure 5) are preferably provided at the top of each siphon leg to prevent boiler pressure from forcing water up into the siphon legs when the buckets are only partially filled as a result of steam condensation 20 in the pipes 44 and 45. Small holes of $\frac{1}{16}$ " diameter are sufficient to prevent this flow until the buckets are filled above the siphon necks.

The pipe 47 terminates in a blow-off valve 50 shown in detail in Figure 7. A tube 51 communicates with the pipe line 47 ahead of the blow-off valve 50 and registers with a pressure gauge 52 in the cab 36 of the locomotive. The pressure within the pipe line 47 is thereby indicated to the operator in the cab and indicates 30 when the valves 46 or 48 are open and water is draining from the buckets.

The blow-off valve 50 comprises a passaged body portion 53 having an inlet 54 for connection to the pipe 47, a sludge water inlet 55 35 for connection with a pipe 56 leading from the bottom portion or mud ring of the boiler and a discharge portion 57 communicating with the pipe line 27 to the steam separator 28.

The body portion 53 is provided with an annular valve seat 58 about a port 59 that provides 40 communication between the inlet portion 54 and the discharge 57. A piston 60 is slidably mounted in the cylindrical portion 61 above the port 59 and is adapted to seat against the annular seat 58 by virtue of pressure in the inlet portion 54 on the relatively large area of the top 60a of the piston.

The piston 60 is provided with an upper cylindrical portion 62 that extends into a recessed plug 63 threaded into the top of the body portion 53 of the valve. The cylindrical portion 62 is provided with a condensate groove 64 to prevent water from being trapped above the cylindrical portion 62.

55 The piston head 60 is also provided with a duct 65 extending therethrough to permit drainage from the inlet portion 54 into the discharge portion 57.

The piston 60 is also provided with an elongated reduced lower end 66 extending through the discharge portion 57 into the sludge inlet portion 55 of the valve for a purpose to be hereinafter described.

60 The body portion 53 is provided with a threaded bore 67 between the sludge inlet 55 and discharge portion 57 thereof for receiving an apertured seat insert 68 through which the end 66 of the piston 60 freely extends. A ball 69 preferably of stainless steel, is adapted to be held 65 in engagement with the insert 68 by means of a coiled spring 70 mounted in a recessed boss or plug 71 which is threaded into the apertured lower end of the body portion 53. The plug 71 is provided with a centering boss 72 and up-standing segmental cylindrical lugs 73 that co-

70 operate to center and position the coiled spring 70.

We have found that the boiler water at the top of the boiler contains relatively greater amounts of foam producing and foam stabilizing substances and have therefore according to this invention collected this water in the buckets 40 and 41. It is known that the water surface and the steam bubble interfaces of boiler water exhibit low surface tension, which means that surface active substances which produce and stabilize foam are positively adsorbed therein. This lowered surface tension induces positive adsorption of other foreign substances, both dissolved and suspended matter, particularly colloidal substances all of which accentuate the production and stabilization of foam.

10 The foam or steam bubbles that are collapsed in the collecting buckets 40 and 41 will naturally contain a higher concentration of the foam producing foreign substances than the solid water withdrawn from the lower portions of the boiler.

15 The collecting buckets are arranged at two different levels with the bucket 40 being designed to collect foam or light water from a level approximately even with the top reading of the water glass on a locomotive boiler. As water accumulates in the bucket 40 and passes above the siphon neck or leg 44a it will flow into the valve 48 through the pipe line 44. The valve 48 opens 20 to discharge water into the pipe line 47. The water in the pipe line 47 is discharged into the blow-off valve 50 in the inlet port 54 thereof on top of the piston head 60. Since the flow from valve 48 will not ordinarily be sufficient to depress the piston 60, the water from the valve flowing through the pipe line 47 passes through the duct 65 in the piston head and is discharged 25 to the steam separator 28 on top of the boiler through the pipe line 27. Any steam is liberated 30 to the atmosphere through the opening 29 of the separator 28 while the water is drained with harmless force to the road bed through the discharge pipe line 30.

35 When water has been completely discharged from the bucket 40 steam will flow through the pipe 44 into the valve 48 thereby causing this valve to close due to the absence of water. The discharge of water from the boiler is then discontinued until water is again accumulated in the bucket 40. The discharge of boiler water from the bucket 40 may be of relatively small magnitude such as three to five gallons per minute. This will cause the valve 48 to be opened 40 for extended periods of time depending upon the nature of the boiler water and the foaming tendencies thereof.

45 Ordinarily the rate of discharge from the bucket 40 will be so arranged that it will be insufficient to completely condition the boiler water to keep foam developments from rising above the level of the cylinder 40. Therefore periodically the foam or light water will develop 50 above the level of foam collector 40 and will be accumulated in the bucket 41. When the water in the bucket 41 reaches a level above the siphon leg 45a of the pipe line 45 it will be discharged 55 into the valve 46. The water will open the valve 46 and flow into the pipe line 47.

60 The combined water streams from the valves 46 and 48 will be in excess of the amount that can be freely discharged through the duct 65 of the piston head 60 in the blow-off valve 50 thus creating a pressure above the piston head in the blow-off valve and causing the piston to be seated 65

70 75

against the valve seat 58. This downward movement of the piston causes the end portion 56 thereof to depress the ball 69 thus communicating the sludge water inlet 56 with the discharge opening 57 and permitting a blowing off of the lower portion of the boiler into the pipe line 21 to the steam separator. The blowing off of the lower portion of the boiler thus prevents the accumulation of excessive solid foreign matter in the boiler and decreases the foaming therein so that the valves 46 and 48 will be closed and the piston 60 will again rise in the blow-off valve to shut off the flow of sludge water from the boiler. Obviously, the discharge from the valve 46 alone may, in some instances, be sufficient to operate the blow-off valve 50 for the discharge of sludge water as, for example, when the valve 48 becomes inoperative.

It should be understood that normally the concentrated or light water in the bucket 40 can be continually discharged without actuating the blow-off valve 50. However when the concentrated or light water accumulates so as to rise beyond the top portion of the siphon leg 45a in the bucket 41, this increased flow is sufficient to open the blow-off valve for the discharge of sludge water from the boiler thereby decreasing the foreign ingredients in the boiler water and lowering the foam. Even if no water collects in the buckets 40 and 41, steam contained in the pipe lines 44 and 45 will eventually condense forming water to open the valves 46 and 48 at infrequent intervals to discharge water. This is beneficial in cold weather to prevent a freeze-up of the blow-off system and assures an opening of the blow-off valve 50 at least at infrequent intervals to remove accumulated sludge.

It should also be understood that the blow-off system can be used without the blow-off valve 50 for discharging sludge water. In other words the collecting buckets can be used alone in connection with valves such as 46 and 48 for removing concentrated water from the boiler.

In Figure 6 there is illustrated another modification of the system wherein the pipe line 45 from the bucket 41 terminates in the valve 46 and discharges water into the pipe line 47 as described in Figure 4. However the discharge pipe 44 from the bucket 40 communicates with a valve 48 of the steam trap type which valve 48 discharges through a pipe 80 into a second steam separator 81 mounted at the lower portion of the boiler. Thus water from the bucket 40 is discharged separately from water from the cylinder 41. The steam separator is provided with a steam discharge opening 82 at the top thereof and a water drain 83 at the bottom thereof. In this manner some of the light or concentrated water is discharged through a separate system and the bucket 41 collects the excessive foam or light water for actuating the blow-off valve to discharge sludge water from the boiler.

From the above description it should be understood that many modifications of the illustrated systems can be used in applying this invention and are within the scope of the invention.

The systems of this invention provide for the controlling of boiler water without excessive and unnecessary blowing off of boiler water such as takes place in the continuous blow-off systems which operate whenever the boiler is in service. With the systems of this invention blowing off is not accomplished after washouts or water changes and does not take place until the boiler water concentration reaches a definite value, for exam-

ple, within seventy-five percent of the maximum allowable concentration. The systems are entirely automatic and carry out the function of maintaining a uniform desirable concentration of boiler water without manual interference. The systems further provide for the most efficient removal of foam forming and foam stabilizing substances with the least waste of boiler water and thus with the least interference with the operating efficiency of the boiler.

The collection of foam forming and foam stabilizing substances in the collapsed foam films will permit the maintenance of higher concentrations of soluble mineral salts in the boiler water, thus materially reducing the waste of water blown out to prevent foaming. Since water blown out from a collapsed foam film source contains higher percentages of the foam forming substances than the main body of boiler water, the percentage of these substances in the boiler water will be materially reduced simultaneously with the increased concentration of dissolved mineral salts in the water. This results in many advantages besides saving of boiler water in that it permits the maintenance of a higher alkalinity of the boiler water without danger of excessive foaming. The maintenance of higher alkalinity reduces the corrosive qualities of the water and will increase the effectiveness of the chemical treatment of the boiler to prevent all types of scale formation.

As pointed out above the system of this invention utilizing basins, buckets and other collecting means for collapsed foam above the normal visible water level, intercepts the foam simultaneously developed in the evaporation zones of the boiler and prevents its reaching the steam outlet.

We are aware that many changes may be made and numerous details of construction may be varied through a wide range without departing from the principles of this invention, and we therefore, do not purpose limiting the patent granted hereon otherwise than necessitated by the prior art.

We claim as our invention:

1. The method of controlling boiler water in operating steam boilers which comprises collecting water directly from the main body of light boiler water only above the normal level of water in the boiler and periodically draining the collected water from the boiler without substantial discharge of steam therewith.

2. The method of controlling foaming of boiler water in operating steam boilers which comprises collecting directly from the main body of water in the boiler, only water from collapsed foam on top of the boiler water and periodically discharging the collected water from the boiler without substantial discharge of steam therewith.

3. The method of controlling foaming of boiler water in operating steam boilers which comprises segregating directly from the main body of water in the boiler, only water from collapsed foam on top of the boiler water, and discharging the segregated water from the boiler when a predetermined amount has been segregated without venting the steam space of the boiler to the atmosphere.

4. The method of controlling foaming in operating steam boilers which comprises collecting directly from the main body of water in the boiler, only concentrated boiler water on top of the boiler water in the boiler, periodically discharging the collected water from the boiler without venting the steam space of the boiler to the atmosphere

and simultaneously blowing off sludge water from the bottom of the boiler.

5. The method of controlling foaming in operating steam boilers which comprises segregating directly from the main body of water in the boiler, only concentrated boiler water from collapsed foam on top of the boiler water, periodically discharging the segregated water from the boiler from below the surface of said water to prevent 10 discharge of steam therewith and simultaneously blowing off sludge water from the bottom of the boiler.

6. The method of controlling foaming in operating steam boilers which comprises collecting directly from the main body of water in the boiler, only water from collapsed foam on top of the boiler water, flowing the collected water from below the surface thereof out of the boiler to prevent discharge of steam with the water and blowing 20 off sludge water from the bottom of the boiler whenever the flow of concentrated water increases beyond a predetermined amount.

7. The method of controlling foaming in operating steam boilers with least possible waste of 25 boiler water which comprises collecting directly from the main body of water in the boiler, only water from collapsed foam on top of the boiler water in the steam space of the boiler, flowing the collected water out of the boiler without substantial 30 discharge of steam therewith and utilizing the flowing water to blow off sludge water from the bottom of the boiler whenever the flow increases beyond a predetermined rate.

8. The method of operating locomotive boilers 35 to control foaming of boiler water therein which comprises collecting concentrated water from collapsed foam on top of the boiler water directly from the main body of water in the boiler in the steam space of the boiler, draining the collected 40 concentrated water through a steam trap from below the level thereof out of the boiler to prevent discharge of steam therewith, flowing the drained water into a blow-off valve and actuating said valve with the flow of water to blow off sludge 45 water from the bottom of the boiler.

9. Apparatus for controlling foaming in operating steam boilers comprising a pair of open topped buckets vertically mounted in the steam space of a boiler and having the bottom ends thereof below the normal water level in the boiler, the top of one of said buckets being at a higher level in the boiler than the top of the other bucket, individual pipe lines extending from outside of the boiler into the buckets and having downwardly 50 turned leg portions terminating in the buckets near the bottoms thereof, steam traps, each at a level beneath the buckets, communicating with said pipe lines for receiving water and steam from the buckets, a discharge line communicating with the steam traps for receiving water therefrom, a water actuated blow-off valve communicating with said discharge line having a restricted passageway accommodating limited flow of water from said line therethrough, said valve being opened by an increased flow of water therein from said line, a sludge pipe communicating with the lower portion of the boiler and with the blow-off valve, and a drain line from said blow-off valve.

10. Apparatus for controlling foaming in steam 70 boilers with least possible waste of boiler water which comprises means for collecting water from collapsed foam at separate levels in the boiler within the light water zone thereof, pipe lines for draining the collected water from the boiler, steam traps below the water collecting means in said

5 pipe lines preventing the passage of steam therethrough, a blow-off valve, a discharge line communicating with said steam traps and with said blow-off valve, a sludge discharge pipe communicating with the valve and with the lower portion of the boiler, means in said valve actuated by flow of water from the steam traps discharge line into the valve for opening and closing the sludge blow-off and a drain line from said blow-off valve for receiving the sludge water and the 10 collected water therefrom.

11. Apparatus for controlling foaming in operating steam boilers which comprises a collecting means mounted in the boiler in communication with the boiler only above the normal water level 15 therein whereby foam can flow into said means directly from the main body of water in the boiler, a pipe line communicating with the lower portion of said means to drain the means, a blow-off valve outside of the boiler communicating with said pipe line, means communicating the blow-off valve with the lower portion of the boiler, and means responsive to periodic liquid flow through the pipe line for actuating said blow-off valve to discharge 20 water from the collecting means and sludge water 25 from the boiler.

12. Apparatus for controlling foaming in operating steam boilers which comprises an open topped bucket vertically mounted in the steam space of a boiler with the lower end thereof below the normal level of water in the boiler and the open top in communication with the light water zone in the boiler, a pipe line extending into the bucket from outside of the boiler and having a downturned leg portion terminating near the bottom of the bucket, a steam trap outside of the boiler below the bucket communicating with the pipe line, said trap being actuated whenever water collected in the bucket overflows the leg portion of the pipe thereby discharging water into the trap 30 until the bucket is emptied below said leg and a discharge line for receiving water from the steam trap.

13. Apparatus for controlling foaming in operating steam boilers comprising a pair of buckets 45 vertically mounted in the steam space of a boiler in communication with the boiler at separate levels above normal water level in the boiler for receiving therein light water formed on top of the boiler water, individual pipe lines extending 50 from outside of the boiler into said buckets and having downwardly turned leg portions terminating in the buckets near the bottoms thereof, steam traps outside of the boiler below the levels of the buckets communicating with said pipe lines for receiving water and steam from the buckets, a discharge line communicating with the steam traps for receiving water therefrom, a water actuated blow-off valve communicating with said discharge line having a passage accommodating a limited flow of water from said line therethrough and means to open the valve actuated by flow of water from said line whenever said flow exceeds said limited amount accommodated by said passage, a sludge pipe communicating with the lower portion of the boiler and with the blow-off valve, and a drain line from said blow-off valve for receiving the water from the steam traps and the sludge water from the blow-off valve.

14. The method of controlling foaming in steam boilers with the least possible waste of boiler water which comprises collecting in a container directly from the main body of boiler water in the steam space of the boiler, concentrated water from collapsed foam on top of the boiler water,

draining the collected water out of the boiler and periodically discharging said water only without discharge of steam therewith until said container is substantially empty.

5 15. The method of controlling foaming in steam boilers with the least possible waste of boiler water which comprises collecting in a container concentrated water from collapsed foam on top of the boiler water in the steam space of the boiler 10 directly from the main body of water in the boiler, draining the collected water out of the boiler, discharging the water only without substantial discharge of steam therewith, utilizing said water to actuate a blowing off of sludge water from the 15 boiler and discharging said sludge water coincidentally with the discharge of water from said water responsive valve.

16. Apparatus for controlling foaming in operating steam boilers which comprises water collecting means in the boiler having the inlet thereof of above the normal water level in the boiler but below the steam outlet, said inlet being in communication only with the main body of light boiler water formed on top of the boiler water for directly receiving light water into the collecting means, a drain line for draining liquid from the collecting means and a liquid responsive valve in said drain line below the collecting means for effecting periodic discharge of liquid from the 30 collecting means, said valve being so constructed and arranged to open upon a predetermined flow of liquid thereto and close upon cessation of said flow.

17. Apparatus for controlling foaming in operating steam boilers which comprises water collecting means in the boiler having the inlet thereof of above the normal water level in the boiler but below the steam outlet, said inlet being in communication with the main body of light boiler 40 water formed on top of the boiler water for directly receiving light water into the collecting means, a drain line extending into the collecting means having a downturned leg portion terminating near the bottom of the collecting means and a liquid responsive valve in said drain line at a level below the collecting means, said valve being so constructed and arranged to open upon a predetermined flow of liquid thereto and close upon a cessation of said flow whereby a rise in liquid level 50 in the collecting means above the downturned leg portion therein effects a siphoning of liquid out of the collecting means into the valve to open the valve for discharge of liquid until the liquid level in the collecting means is below the leg portion whereupon the liquid flow to the valve ceases and the valve closes to prevent discharge of steam.

18. The method of controlling foaming in operating steam boilers which comprises collecting directly from the main body of water in the boiler only the light water formed above the normal level of water in the boiler, periodically siphoning the collected water whenever the same exceeds a predetermined level and discharging said water without venting steam in the steam space to the atmosphere.

19. Apparatus for removing foam producing and foam stabilizing ingredients from boiler water in operating steam boilers which comprises means 70 in the upper portion of the boiler so positioned as to collect directly from the main body of water in

the boiler, only light water and water from collapsed foam on the boiler water, a drain pipe communicating with the lower portion of said means to remove collected water therefrom, and a valve in said pipe for controlling the flow of water therethrough. 5

20. Apparatus for controlling foaming in operating steam boilers which comprises an open-topped bucket vertically mounted in the steam space of the boiler with the lower end thereof 10 below the normal level of water in the boiler, a pipe extending into the bucket from outside of the boiler and having a downturned leg portion terminating in the bucket near the bottom thereof, said leg portion being vented at the top thereof, a steam trap at a level below the bucket communicating with said pipe line and a discharge line from said steam trap adapted to receive water therefrom to discharge said water whenever it overflows from the steam trap. 15

21. Apparatus for controlling foaming in steam boilers comprising means for collecting concentrated water at the top of boiler water in an operating steam boiler, pipes for draining the collected water from said means at different levels 25 therein, steam traps below the level of the collecting means communicating with each of said pipes, a discharge line communicating with the steam traps to receive water therefrom, a blow-off valve casing in communication with the lower portion of the boiler, a piston slidably in said valve casing, means in the valve casing operated by the piston to open and close the valve, said discharge line terminating in said valve casing above the piston therein to feed water from the traps to the 35 piston for operating the piston and a duct in said piston allowing drainage of a predetermined flow of water from the discharge line, said blow-off valve parts being so constructed and arranged that a flow greater than a predetermined flow will 40 depress the piston to open the valve and blow off the boiler.

22. Apparatus for controlling foaming in operating steam boilers which comprises a collecting means mounted in the boiler between the steam 45 outlet and main evaporation zone of the boiler in direct communication with the light boiler water above the normal water level therein and positioned to collect only light water and foam generated in the boiler that might otherwise continue 50 toward the steam outlet and be entrained in the steam delivered from the boiler, a pipe line communicating with the lower portion of said means to drain the means and a liquid responsive valve in said pipe line below the collecting means for 55 effecting periodic discharge of the collected material.

23. The method of controlling foaming in operating steam boilers which comprises collecting foam generated in the boiler directly from the 60 main body of water in the boiler only at a level above the normal water level in the boiler and at a point between the steam outlet and main evaporation zone of the boiler to prevent entrainment 65 of foam and moisture in the steam issuing from the boiler and periodically draining the collected foam from the boiler without venting steam in the steam space to the atmosphere.
